UNITED STATES PATENT OFFICE

2,562,337

COMBINATION COOLING AND FLUID HEATING UNIT

Francis J. Smith and Woodrow W. Smith,
Miami, Fla.

Application July 22, 1949, Serial No. 106,278

2 Claims. (Cl. 219—39)

1

This invention relates to heat-exchanging devices, and more particularly to a combination heating and ventilating unit for heating or cooling a room, dwelling, apartment, or other space.

A main object of the invention is to provide a novel and improved heating or cooling unit which may be installed in the wall of a room or the like, said unit being very simple in construction, very compact in size, and being adapted to provide either ventilation and cooling of a room, or to provide heating of the room when required.

A further object of the invention is to provide a novel and improved packaged ventilation and heating unit adapted to provide ventilation and cooling by circulation of air from outside a room or dwelling space, or alternatively to heat the room or space and to maintain said room or space at a predetermined temperature.

Further objects and advantages of the invention will become apparent from the following description and claims, and from the accompanying drawings, wherein:

Figure 1 is a vertical cross-sectional view taken through an improved combination cooling or heating unit constructed in accordance with the present invention;

Figure 2 is a fragmentary cross-sectional view taken on line 2—2 of Figure 1;

Figure 3 is a fragmentary longitudinal cross-sectional view taken through a portion of the electrical water-heating element employed with the unit of Figure 1;

Figure 4 is an enlarged front end elevational view of the heating element of Figure 3;

Figure 5 is a vertical cross-sectional view taken through the wall of a room showing a typical installation of the improved cooling and heating unit of Figure 1.

Referring to the drawings, the unit comprises a rectangular housing 11 provided at its rear wall with a screen 12 and provided at its front wall with the horizontally-pivoted transverse louvers 13 which are freely hinged to swing outwardly when the air pressure builds up inside the housing and to allow air to exhaust therefrom. However, the lower marginal portions of the louvers cannot swing counterclockwise from their closed positions shown in Figure 1, since said lower marginal portions come into abutment with the upper marginal portions of subadjacent louvers.

Rotatably mounted in the housing is a shaft 14 carrying at its forward end the fan blades 15. Secured on the rear end of shaft 14 is a

2

pulley 16 on which is mounted a belt 17 driven by an electric motor 18 secured to the top wall of the housing. Motor 18 is of the reversible type and is connected by a suitable circuit, not shown, which includes a reversing switch, to a suitable power source.

The bottom of the housing 11 comprises a radiator 19 provided with the water coils 20, suitable radiating fins being mounted on the coils.

Air may flow through radiator 19 in either an upward or a downward direction. Designated at 21 is a settable thermostatically-controlled electric water heater having an intake conduit 22 connected to the bottom coil of the radiator 19 and an outlet conduit 23 connected to the top coil of said radiator. The water heater 21 may comprise an elongated cylindrical housing 24 containing a heating element 25. Secured to the front end of housing 24 is a chamber 26 in which is mounted a bimetallic arm 27 connected to a temperature-sensitive expandable bimetallic helix contained in a tubular chamber 28 extending into the housing 24. One terminal of heater winding 25 is connected to a stationary contact 29 located in chamber 26 adjacent the free end of bimetallic arm 27. The other end of arm 27 is connected to a wire 30. The remaining terminal of heater winding 25 is connected to a wire 31. Movement of the free end of thermostat arm 27 away from contact 29 is controlled by a manually-adjustable stop screw 32 provided with an external setting arm 33. The thermostat arm 27 will move out of contact with element 29 when the temperature inside the heater housing 24 rises beyond a value determined by the setting of arm 33.

Wires 30 and 31 are connected to a suitable power source, and may include in series there-with a room thermostat switch, such as shown at 34 in Figure 5.

The radiator 19 is provided with an expansion chamber 35 to allow for expansion of the heating unit during the heating cycle. Said radiator is also provided with a relief valve 36 allowing steam to escape from the radiator coils in case of overheating of the water therein.

Referring to Figure 5, the unit may be mounted in the wall 37 of a building with the screen 12 flush with the inside wall surface of a room. The wall 37 is provided below the unit with a register 38 which may include an air filter 39. A suitable air duct 40 is employed to connect the bottom of housing 11 with the register 38.

Designated at 41 is a two-way switch of conventional construction mounted on a wall of the

room and connected in circuit with the motor 18. The switch has the push buttons 42 and 43. Push button 42 controls energization of the motor 18 in one direction, while button 43 controls energization of said motor in the opposite direction. Actuation of push button 43 causes motor 18 to drive the fan blades 15 clockwise, as viewed in Figure 2, causing air to be drawn from the room through screen 12 and to be exhausted outwardly through the louvers 13. By opening a window or door in the room, fresh air will be drawn into the room, providing air circulation and cooling of the room. A certain amount of the air is recirculated by moving into housing 11 through screen 12, downwardly through duct 40, and back into the room through register 38. This recirculation increases the cooling of the room by causing air to move from the floor of the room upwardly toward the ceiling.

Actuation of push button 42 causes motor 18 to be driven in the opposite direction. Push button 42 may also be employed to actuate a suitable switch to control the energizing circuit of the heater winding 15 in conjunction with the thermostat switch 34 and the heater contact elements 27 and 29. The fan blades 15 now rotate counterclockwise, as viewed in Figure 2. Under these conditions air is driven out of housing 11 into the room through screen 12, reducing the pressure in the housing, whereby louvers 13 remain closed. Air will be drawn from the lower portion of the room through register 38 and filter 39 and upwardly through duct 40 through the radiator 19, where the air is heated, and then is discharged into the room through screen 12.

The room thermostat 34 is preferably connected in the supply line to the motor circuit controlled by push button 42, so that when the room temperature reaches the value corresponding to the thermostat setting the motor circuit is opened. This also opens the energizing circuit for the heater 21, since, as above explained, said energizing circuit is likewise controlled by thermostat 34, and may be connected in parallel with the motor circuit controlled by push button 42. Therefore, operation of the heating unit and fan automatically stops when the temperature of the room rises to the desired value.

As shown in Figure 5, water may be furnished to the heater 21 from a suitable source of supply through a conduit 44 entering duct 40 and provided with an external hand valve 45. The conduit 44 may be provided inside duct 40 with a suitable pressure-reducing valve 46, so that water may be furnished to the heater at only moderate pressure. Valve 45 remains open at all times and need be closed only for draining the unit or for repairs.

Figure 5 illustrates merely one manner of using the self-contained heating and cooling unit of the present invention. The unit may be installed in various other positions different from that shown in Figure 5. For example, the unit may be installed horizontally instead of vertically, as shown, as in a ceiling, with the radiator 19 disposed vertically, a suitable duct similar to duct 40 being employed to connect the unit to a register in the wall of the room below.

Any desired fluid may be employed as the heat-

ing medium. Any desired suitable type of fluid heater may be substituted for the electric heater 21, such as a heater fluid by gas, oil, or other fuel.

While a specific embodiment of a self-contained heating and cooling unit for ventilating or heating a room or dwelling space has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a heating and ventilating device, a hollow housing having its opposite ends open and an open bottom, a radiator spanning the open bottom of said housing and secured to the adjacent side walls of the latter, means operatively connected to said radiator for providing heat to the latter, means positioned in one of the open ends of said housing and carried by the adjacent side walls of the latter for opening and closing said open end responsive to a change of pressure within said housing, a screen positioned in the opposite open end of said housing and secured to the adjacent side walls of the latter, a shaft rotatably mounted within said housing at right angles to said opposite open ends, a plurality of blower vanes secured to one end of said shaft, and a reversible motor mounted within said housing on one of the side walls of the latter and operatively connected to the other end of said shaft.
2. In a heating and ventilating device, a hollow housing having its opposite ends open and an open bottom, a radiator spanning the open bottom of said housing and secured to the adjacent side walls of the latter, means operatively connected to said radiator for providing heat to the latter, a plurality of overlapping louvers positioned within one of the open ends of said housing and operatively mounted to the adjacent side walls of the latter for limited pivotal movement between open and closed positions, said louvers being movable to their open and closed positions in response to a change in pressure within said housing, a screen positioned in the opposite open end of said housing and secured to the adjacent side walls of the latter, a shaft rotatably mounted within said housing at right angles to said opposite open ends, a plurality of blower vanes secured to one end of said shaft, and a reversible motor mounted within said housing on one of the side walls of the latter and operatively connected to the other end of said shaft.
